RECORD BINDER

Charles H. Lockwood, Atchison, Kans.

Application March 4, 1943, Serial No. 477,909

3 Claims. (Cl. 129—24)

This invention relates to improvements in record binders, and refers more particularly to binders for loose leaf records, such as Federal, State, county or municipal records.

The salient features of novelty reside in the construction of the backbone or rigid support which extends longitudinally of the rear edge of the sheets to be bound, and the manner in which this support or backbone is attached to the covers or sides of the binder by channel members rigidly held in an upright position upon the inner face of the backbone.

Heretofore it has been conventional practice to form the backbone of a substantially semi-cylindrical piece of metal, or of relatively rigid fiber board, or other suitable resistant material. The channel members and post assemblies which support the loose leaf sheets and fasten the sides when hinged to the edges of a backbone of this type, produce difficulties in properly aligning the posts and channels when the record sheets are inserted or removed from the binder.

Another advantage of the use of a solid backbone is the fact that the ridges or hubs on the outer curved surfaces conventional to this type binder may be formed on the backbones by turning, thus reducing labor and expense now required to apply separate pieces to form the hubs.

Upon the inner face or flat surface of the backbone are parallel grooves which receive engaging members or slides which hold the channels to the backbone, and accurately space the channels apart so that the bridging posts which hold the record sheets fall readily in position and are easily engaged by the pintle slides which hinge the posts and sides to the channels. Wedge members or dowels inserted in the ends of the grooves prevent the channel slides from being displaced longitudinally.

Pintle slides which hold the ends of the posts to the channels and hinge the sides to the channels are so designed that in one position they permit removal of the record sheets by releasing the posts while remaining in engagement with the hinges, and in a second position engage both the hinges of the covers and the ends of the posts.

In the accompanying drawing, which forms part of the instant specification and is to be read in conjunction therewith, and in which like reference numerals are used to indicate like parts in the various views,

Fig. 1 is a side elevational view of the binder with parts broken away,

Fig. 2 is a sectional view taken along the line 55

2—2 of Fig. 1 in the direction of the arrows. The lower portion of the view has the sheets removed to expose the grooves in the backbone,

Fig. 3 is a view taken along the line 3—3 of Fig. 1, in the direction of the arrows,

Fig. 4 is a view taken along the line 4—4 of Fig. 1, in the direction of the arrows.

The binder consists of a backbone 1 which has an outer curved surface, and an inner relatively flat surface. On the curved outer surface are usually formed a plurality of ridges 1a, known in the art as hubs. The backbone here shown is of wood and the hubs formed on the curved outer surface were turned by means of a lathe. It will be understood that while wood is selected as the solid material for the backbone, any suitable solid material which is inexpensive and can be easily shaped and worked and which is relatively light in weight and capable of withstanding the normal abuse to which record books are subjected is satisfactory.

Longitudinally of the backbone as suggested are two parallel grooves 1b, preferably formed in the shape of a dovetail, as shown in cross section in Figs. 3 and 4. Positioned upright upon the flat inner surface of the backbone are channel members 2 which have a hollow body, and plates 2a which lie flat against the surface of the backbone. Extensions of the plates 2a are formed as angle slides 2b, which fit the contour of the longitudinal grooves in the backbone and hold the channels 2 in an upright position at right angles to the flat inner surface of the backbone. While the grooves in the backbone are dovetailed in shape, and the angle slides 2b are formed to fit these grooves, it should be understood that this particular shape which has been chosen for the grooves is not arbitrary, but may be varied as long as the channels are held rigidly at right angles to the backbone. Furthermore, it is desirable that the width of the groove at the surface of the backbone be somewhat less than the width at the bottom of the groove, thus preventing outward displacement of the slides from the grooves, that is, requiring the removal of the channels from the backbone by sliding the channels lengthwise of the backbone until the slide passes entirely out of the groove.

To hold the channels in place on the backbone and to prevent longitudinal displacement of the slides in the grooves, dowels or wedges 3 are slipped into the ends of the grooves frictionally wedging the slides against the sides of the grooves.

Within the hollow body portion of the channels

2 are pintle slides 4, which have a plurality of pintle extensions, two of which are relatively long and designated as 4a, and four of which are shorter in length and designated as 4b.

The top edges of the channels are cut away at predetermined locations, as shown at 2c, to accommodate the eyelet ends of hinges 5 by means of which the covers or sides 6 of the binder are attached to the channel, and also to receive eyelets in the ends of posts 7 which hold the record sheets.

The hinges 5 may be formed of strips of a suitable material, such as metal, plastic or fiber. Fiber is now being used in place of metal due to war conditions. The ends of the hinges are embedded in the cover between the layers of plywood and pressed wood which form the material of the cover, and are held in position in the plywood by rivets 8, as shown in Fig. 4. Both the sides and the backbone are usually covered by suitable flexible material, such as leather, buckram, canvas or "fabrikoid," shown at 9. This cover material is principally for appearance and facilitates cleaning of the binder. The record sheets are shown at 10.

The manufacture of the backbone is relatively simple. Wood, usually magnolia which is relatively light and tough and has a grain somewhat similar to maple, is cut with a flat side and a curved side, and after grooving the separate pieces are mounted upon a mandrel and the hubs 1a turned on the curved surfaces. The channels are formed of light metal strips in relatively simple forming operations. The manufacture of the sides and pintles is conventional except that the design of the pintles is unique in that it permits posts which hold the record sheets to be released on one or both sides in order that the record sheets may be removed without disturbing the covers or sides of the binder.

It is evident that the manner of attaching the channels to the backbone besides providing a rigid structure, accurately spaces the back edges of the sheets from the backbone and maintains a definite spacing of the channels so that the posts can be readily assembled or removed when inserting record sheets or removing record sheets from the binder.

The angle slides of the channels with the grooves of the backbone provide a rigid assembly of the binder and eliminate tedious, expensive riveting or screwing operations heretofore necessary in attaching channels to the binder.

The dowels or wedges which hold the slides in place besides serving this function fill the grooves and render the backbone more rigid. The groove and slide arrangement for attaching the channels also positively controls the spacing between the

channels throughout the length of the backbone, thus facilitating assembly and ease in removing and inserting the posts when record sheets are inserted or removed from the binder. It has been found that the abutment of the posts on the edges of the sides holds the record sheets in place while the opposite ends of the posts are fastened in the channels at the opposite side of the binder.

From the foregoing it will be seen that the invention is one well adapted to attain all of the ends and objects hereinbefore set forth, together with other advantages which are obvious and which are inherent to the structure of the device.

It will be understood that certain features and sub-combinations are of utility and may be employed without reference to other features and sub-combinations. This is contemplated by and is within the scope of my claims. It is further obvious that various changes may be made in details within the scope of my claims without departing from the spirit of my invention. It is, therefore, to be understood that my invention is not to be limited to the specific details shown and described.

Having thus described my invention, I claim:

1. In a record binder having a rigid backbone, upright channels fixed thereto, binder sides hinged to the edges of the channels and posts bridging said channels, the improvement which comprises slidably engaging the backbone and channels, said engagement including longitudinal grooves in the backbone, and elongated members on the channels adapted to slide in the grooves of the backbone.

2. In a record binder having a rigid backbone, upright channels fixed thereto, binder sides hinged to the edges of the channels and posts bridging said channels, the improvement which comprises slidably engaging the backbone and channels, said engagement including longitudinal grooves in the backbone, elongated members on the channels adapted to slide in the grooves of the backbone, and dowels insertable in the ends of the grooves to hold the slide members of the channels fixedly in said grooves.

3. In a record binder having a rigid backbone, upright channels fixed thereto, binder sides hinged to the edges of the channels and posts bridging said channels, the improvement which comprises slidably engaging the backbone and channels, said engagement including longitudinal grooves in the backbone narrower at the top than the bottom, and elongated members on the channels adapted to slide in the grooves of the backbone.

CHARLES H. LOCKWOOD.
